Primary Examiner — Daniel J Domino*Assistant Examiner* — Samina Vieth(74) *Attorney, Agent, or Firm* — Paratus Law Group, PLLC(57) **CLAIM**

The ornamental design for a cover for electronic communications device, as shown and described.

DESCRIPTION

FIG. 1 is a front, top, and right side perspective view of a cover for electronic communications device, showing my new design;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof;

FIG. 8 is a front, top, and left side perspective view thereof;

FIG. 9 is a back, top, and left side perspective view thereof; and,

FIG. 10 is a back, bottom, and right side perspective view thereof.

The broken lines shown in FIGS. 3, 9, and 10 depict portions of the cover for electronic communications device and form no part of the claimed design.

1 Claim, 8 Drawing Sheets(56)
